(57) **CLAIM**

I claim the ornamental design for the combined backpack and luggage, as shown and described.

DESCRIPTION

FIG. 1 is a front elevational view of a combined backpack and luggage;

FIG. 2 is a back elevational view thereof;

FIG. 3 is a left side elevational view thereof;

FIG. 4 is a right side elevational view thereof;

FIG. 5 is a bottom plan view thereof;

FIG. 6 is a top plan view thereof;

FIG. 7A is a right side view of the luggage with the backpack removed;

FIG. 7B is a right side view of the backpack detached from the luggage with the flap released to reveal the straps; and,

FIG. 7C is a right side view of the backpack detached from the luggage with the flap rolled up under the secured straps.

The broken lines shown on the flap in FIGS. 1 and 6 illustrate a portion of the article and form no part of the claimed design.
